Des. 210,523

Patented Mar. 19, 1968

210,523

AUTOMATIC PIPETING UNIT

Leonard N. Albrecht, Mill Valley, Calif., assignor to
Warner-Lambert Pharmaceutical Company, Mor-
ris Plains, N.J., a corporation of Delaware

Continuation-in-part of design application Ser. No. 2,952,
July 6, 1966. This application Apr. 14, 1967, Ser. No.
7,137

Term of patent 14 years

(Cl. D16—2)

Fig. 1

Fig. 2

FIG. 1 is a front perspective view of an automatic pipeting unit showing my new design; and

FIG. 2 is a rear perspective thereof.

This is a continuation-in-part of design application Ser. No. D. 2,952, filed July 6, 1966 and now abandoned.

I claim:

The ornamental design for an automatic pipeting unit, as shown and described.
